Primary Examiner — Joseph Kukella*Assistant Examiner* — Yuan Yuan(74) *Attorney, Agent, or Firm* — Workman Nydegger(57) **CLAIM**

The ornamental design for a tent, as shown and described.

DESCRIPTION

FIG. 1 shows a first front perspective view of a tent according to the present invention;

FIG. 2 shows a second front perspective view of the tent of FIG. 1;

FIG. 3 shows a rear perspective view of the tent of FIG. 1;

FIG. 4 shows a front view of the tent of FIG. 1;

FIG. 5 shows a rear view of the tent of FIG. 1;

FIG. 6 shows a first side view of the tent of FIG. 1;

FIG. 7 shows an opposite side view of the tent of FIG. 1; and,

FIG. 8 shows a top view of the tent of FIG. 1.

No claim is made to a bottom view of the tent shown in the Figures.

Any broken lines shown are directed to portions of the tent which are not claimed.

1 Claim, 6 Drawing Sheets(56)
